DESIGN FOR A BELT FOR PERSONAL WEAR

Harry Cohen, New York, N. Y.

Application June 17, 1936, Serial No. 63,345

Term of patent 3½ years

To all whom it may concern:

Be it known that I, Harry Cohen, a citizen of the United States of America, residing in city of New York, county of New York and State of New York, have invented a new, original, and ornamental Design for a Belt for Personal Wear, of which the following is a specification, reference being had to the accompanying drawing, forming part thereof.

Fig. 1 is a front view of a belt for personal wear showing my new design.

Fig. 2 is a cross-sectional view taken on line 2—2 of Fig. 1.

The design is continued over the entire outer face of the belt which is completed by the dotted line in Fig. 1.

The light circular elements on the belt represent raised embossed areas which constitute the design motif.

I claim:

The ornamental design for a belt for personal wear substantially as shown and described.

HARRY COHEN.
